UNITED STATES PATENT OFFICE.

FREDERICK A. HART, OF NEW BRITAIN, CONNECTICUT, ASSIGNOR TO REMINGTON TYPEWRITER COMPANY, OF ILION, NEW YORK. A CORPORATION OF NEW YORK.

TYPEWRITING MACHINE.

Application filed June 22, 1922. Serial No. 570,220.

To all whom it may concern:

Be it known that I, FREDERICK A. HART, citizen of the United States, and resident of New Britain, in the county of Hartford and State of Connecticut, have invented certain new and useful Improvements in Typewriting Machines, of which the following is a specification.

My present invention relates to paper feeding and controlling mechanism for typewriting machines and its general object is to provide new and improved mechanism of the character stated. More specifically my invention has to do with what is commonly known as tally roll mechanism, and has for its object the production of improved tally roll mechanism having a number of novel features.

To the above and other ends which will hereinafter appear my invention consists in the features of construction, combinations of devices and arrangements of parts herein-after described and particularly pointed out in the claims.

Referring generally to the present embodiment of the invention in some of its new and improved features of construction, the mechanism is constructed as a separate unit, composed of the tally roll mechanism proper and a support therefor, detachably and movably mounted on the carriage of the typewriting machine. The tally mechanism proper embodies rotary supply carriers for both work sheets or paper and reproduction sheets or carbon strips, both such sheets being friction driven, being advanced when the platen is turned or line spaced through co-operation between the platen and the regular carriage feed rolls. There is also provided a take-up or receiving device for the tally strip in the form of a rotary carrier having frictional connections with the platen. The tally roll mechanism or contrivance is adjustable on its support so that it may be set at any desired position lengthwise of the platen or may be constructed so as to carry sheets or strips substantially as wide as the full length of the platen, being thus adapted for the handling of proof sheets, sales sheets, etc. The method of mounting and controlling the carbon sheet or strip is such as to permit ready access to the tally strip or proof sheet at all times so that inspection and the making of cor-

rections is greatly facilitated as compared with prior constructions. There is provided an improved rewind for the carbon strip combined with a stop or arresting device which is automatically set so as progressively to vary the feed of the carbon, thus thoroughly exhausting its reproducing surface. The take-up or receiving roll as well as the delivery or pay-off roll for the tally strip are provided with locking devices to prevent improper unwinding, the locking device for the delivery roll being automatically controlled. There is also provided a knife bar or severing device for the cutting of the used strips said device being conveniently controlled and also having the function of a paper guide. Other novel features of my invention will be referred to hereinafter.

In the accompanying drawings which illustrate the preferred form of my invention applied to the carriage of a No. 11 Remington typewriting machine,

Fig. 1 is a fragmentary end view partly in section of said Remington carriage and its mounting, my invention being shown in place on said carriage.

Figs. 2, 3 and 4 are operating views of stop devices to be hereinafter referred to in detail.

Fig. 5 is a front elevation partly in section of some of the parts shown in Fig. 1.

Fig. 5^a is a fragmentary sectional view of a detail.

Fig. 6 is a side elevation of the tally roll mechanism as the parts appear when the platen feed rolls are released.

Fig. 7 is a vertical sectional view taken on a plane indicated by the section line 1-1 in Fig. 5 and looking in the direction of the arrows at said line.

Fig. 8 is a substantially horizontal sectional view taken on a plane indicated by the section line 2-2 in Fig. 7 and looking downward in the direction of the arrows at said line.

Fig. 9 is a perspective view of the knife bar and its mounting.

Fig. 10 is a fragmentary elevation partly in section, showing the frictional driving connection between the platen and the tally strip take-up roll.

As appears from Figs. 1 and 2, the top plate 1 or upper framing of the Remington

typewriting machine is provided with posts or lugs 2 and 3 to which are secured fixed grooved guide rails 4 and 5, said rails co-operating through anti-friction rollers 6 with the front and rear grooved bars 7, 8 of a rectangular carriage truck that further comprises end bars 9. Shiftably supported on the carriage truck is a platen frame or carrier comprising end bars 10 and a connecting cross bar 11, the latter underlying a cylindrical or roller platen 12 whose axle or spindle 13 projects through openings indicated at 14 in the end bars 9, the platen and its frame being adapted to shift up and down on the truck, the shifting movements being determined by stop devices, not shown, which project into the openings 14 at its top and bottom. Co-operative with the platen are the usual paper feeding devices comprising main and secondary feed rollers conventionally illustrated herein and numbered respectively 15 and 16, these feed rollers normally co-operating with the platen to feed or advance the paper thereover, but being adapted to be thrown off or released by releasing devices comprising a releasing shaft 17 which extends from side to side of the platen frame and is supported in the end bars 10. Said shaft is provided near its left-hand end with a release key comprising an upstanding crank arm 18 suitably secured to the releasing rock shaft 17 and provided with a horizontal portion or off-set 19 from which rises a finger-piece or key portion 20. The engaged or operated position of the feed rollers 15 and 16 is illustrated in Figs. 1 and 7 while the throw-off or released position is illustrated in Fig. 6, the release being effected through well-known connecting means by rocking the shaft 17 as by pushing the release key 20 back from the Fig. 1 position to the Fig. 6 position. Operatively connected with the right-hand end of the platen 12 is a line spacing ratchet wheel 21 with which co-operates a line spacing pawl 22 supported from the platen axle and connected by a link 23 with a bell crank 24 pivoted at 25 on the right-hand end bar 9 and connected by a link 26 with a crank arm 27 fixed to the rear end of a spring pressed rock shaft 28, said rock shaft extending forward above and parallel with the right-hand end bar and terminating in a downward extension or handle 29. The rock shaft is mounted to rock in a bearing 30 fixed to the right-hand end bar 9 and as is well understood when the line spacing handle or finger-piece 29 is pulled toward the right it is effective to actuate the pawl 22 to co-operate with the wheel 21 to turn the platen through a line space distance and is also effective to restore the platen and platen carriage comprising the platen frame and the truck from left to right to position the platen for beginning a new line of writing.

The usual key operated type bars or printing instrumentalities are provided but are not shown herein except fragmentarily in Fig. 7 where the outer end portion of a type bar 31 is shown in the position it will occupy just prior to co-operating with the front face of the platen 12 to print, the printing portion of the ribbon 32 being interposed at this time between the type on the type bar and the printing point *p* as shown in said Fig. 7.

The support for the tally strip mechanism proper comprises two angular brackets or side members 33 (Figs. 1 and 5) comprising long horizontally disposed arms 34 joined to which are shorter upright arms 35. At their elbow portions the two brackets 33 are connected by a tie or cross rod 36, the ends of which are reduced and threaded to pass through holes in the brackets and may receive clamping nuts 37 whereby the brackets and the tie rod are rigidly secured together. The longer arms 34 of the members 33 are horizontally disposed, extending from above the platen forward to the usual scale bar secured to the truck bar 7, the arms converging slightly from the rear towards the front, their outer ends being formed with holes which receive screw pivots 38, whereby the supporting frame comprising the brackets 33 and the tie rod 36 is pivotally connected to the carriage truck and is adapted to shift on said screw pivots 38 as pivotal centers when the platen and platen frame are shifted to change case, thereby maintaining the tally roll mechanism proper in substantially the same relationship with the platen in both lower and upper case positions. The tally strip contrivance or mechanism proper is mounted on the cross rod 36, which is disposed slightly above the platen, and on a rock shaft 39 which bears in openings in the upper end portions of the upright arms 35, said rock shaft being parallel with the tie rod 36 and somewhat above the same, but in a plane slightly rearward of the tie rod. The rock shaft is adapted to turn freely in its bearings but is prevented from longitudinal movements therein by collars 40 which are secured to the rock shaft 39 by set screws 41 inside the arms 35 with which arms said collars co-operate to prevent the rock shaft from moving endwise in either direction.

The tally strip contrivance or mechanism proper is mounted so that it may be adjusted along the supports or rods 36 and 39 for co-operation with the platen at any desired position longitudinally thereof, said contrivance comprising upright frame plates 42 having a slight rearward inclination (Figs. 1, 5, 5^a, 7, 8 and 10). The lower end portions of the frame plates 42 are connected or tied together by a sleeve 43 which fits over and bears on the rod 36,

said sleeve having reduced and threaded ends which pass through openings in the frame plates 42 and outside said frame plates receive clamping nuts 44 which hold the plates 42 and sleeve 43 in rigid relationship. (Fig. 8). It will be understood of course that the width of the sub-frame composed of the frame plates 42 and sleeve 43 may be altered by changing the length 10 of the sleeve, and that accordingly as the proof sheet or tally sheet or strip is wide or narrow, the sub-frame may be substantially co-extensive in length with the length of the platen as one limit, or may be considerably narrower than shown in the drawing. The frame plates 42 are perforated to permit the passage therethrough of the upper rod 36, certain parts intervening between the rod and the frame plate at the 15 left-hand side as will be hereinafter explained. Bearing on the sleeve or hollow rod 43 inside the frame plates 42 are two metal disks or friction rollers 45 which are adapted to bear rotatably on the upper surface 20 of the platen for motion transmitting purposes. In order to insure sufficient friction between the friction rollers and the platen it is preferred to supplement the gravity of the tally roll contrivance and its support by spring means, and accordingly a pair of coiled draw springs 46 are provided, one arranged at each side of the machine. The upper end of each spring 25 46 is hooked over a pin 47 projecting laterally from the adjacent arm 35 while the lower end of each spring is connected to a hook contrivance 48 which in turn is anchored to the rock shaft 17. The tendency of these springs 46 is to pull the frame 33, 30 36 downward about its pivots 38 and constantly to maintain the friction rollers 45 in contactive resilient engagement with the top of the platen 12 so that rotary movements of the platen will be transmitted 35 to the friction rollers.

The sub-frame 42, 43 provides a support for the several rotary carriers or mandrels comprised in the tally device or contrivance, there being three of such carriers 40 in the present instance, viz., a carrier for delivering or supplying the tally strip, a carrier for receiving or taking up the tally strip after it has been fed around the platen and written upon, and a carrier or support 45 for the roll of transfer material or carbon paper, the last named carrier being arranged at the top of the sub-frame, the tally supply carrier being arranged next below and the take-up carrier being lowermost and co-operating with the friction rollers 45. Considering first the construction and mounting of the delivery or supply carrier or mandrel, Figs. 1, 5 and 7, said mandrel designated as a whole by the reference numeral 49 comprises primarily a hollow tube or core piece 50, end plugs or bearing devices 51 and 52, and heads or flanges 53 and 54. The tube 50 and plugs 51 and 52 are suitably secured together as by screws 55 and 56. The left-hand flange 53 is rigid with a hub piece 57 and said hub piece and the plug 51 are perforated to afford passageway for a shaft or rod 58 which extends into the core or tube 50 and also projects outward beyond the hub 57 50 and bears in an opening in the left-hand frame plate 42. Within the tube 50 the shaft 58 bears in a countersink or depression indicated at 59 formed in the end piece 52. The shaft 58 is spring mounted, 55 being surrounded within the tube 50 by a coiled spring 60 which is confined between the inner end of the plug 52 and a collar 61 pinned to the shaft at 62, said spring normally maintaining the collar in contact with the inner end of the plug 51 as shown in Fig. 5. The outer end of the shaft 58 is formed with a depression or nick 63 for the reception of a tool by which it may be pushed rightward endwise and forced through its bearing opening in the frame plate 42, against the spring 60. The shaft 58 may thus be slid rightward in its bearing 59 and through the end plug 51 sufficiently to clear the frame plate 42, enabling 60 the supply carrier 49 to be withdrawn. Referring now to the manner of supporting the carrier 49 on the right-hand frame plate 42 it will be observed particularly from Fig. 5 that the end plug 52 is formed at its right-hand end portion with a series of circular portions or faces of varying diameters indicated respectively at 52^a, 52^b, 52^c and 52^d. The flange 54 fits over the face 52^b and abuts against the right-hand side of the shoulder formed between it and the face 52^a. The face 52^d engages in a bearing opening or depression indicated at 64 in a hollow bearing member or housing 65 which is suitably secured in the right-hand frame plate 42. This may be done by forming the housing with a reduced shoulder portion 66 at its inner end which is passed through an opening of suitable diameter in the frame plate and is then upset or spread at its inner end, thus clamping the housing to the frame plate. The housing also provides a support for a key member comprising a body portion 67, a head 68 which is cylindrical in shape and bears in the depression 64, terminating at its inner end in a flat sided lug or key portion 69 which normally fits in a slot or kerf 70 cut in the outer face of the plug 52. Projecting rightwardly outside the housing 65 the body portion of the key member is reduced as indicated at 67^a and threaded to receive a finger button or thumb nut 71 which is screwed on the reduced portion, being adapted to abut against the right- 70 75 80 85 90 95 100 105 110 115 120 125 130

hand end of the body portion 67. Surrounding said body portion inside the housing is a coiled spring 72 which reacts against the housing and normally maintains the key 69 engaged with the slot 70 so that turning movements applied to the finger button 71 will be transmitted to the supply carrier 49. The key affords a convenient means of turning the carrier, thus facilitating the insertion and winding up of short work sheets, such as sales sheets, etc. It will be observed that the reaction of the spring 60 through the collar 61 and the end piece 52 insures that normally the end supports of the supply carrier, constituted at the left by the shaft 58 and at the right by the surface 52^b, shall suitably be maintained engaged with their bearings on the frame plates 42. By pushing in on the shaft 58 as described it may be withdrawn far enough from its associate frame plate to enable the entire supply carrier to be slipped out of place. Such withdrawal does not affect the key member 67, 69 since the leftward action of its spring 72 is limited by the engagement of the button 71 with the outer face of the housing or socket piece 65. On the other hand, the key member may be withdrawn from engagement with the supply carrier by pulling rightward on the finger button 71, depressing the spring 72 and withdrawing the lug 69 from the slot 70.

In addition to the flange or head 54 the bearing portion or face 52^b supports a ratchet wheel 73 and a dished plate 74, the ratchet wheel being confined between the plate 74 and the head or flange 54 and the three being suitably secured in place on the bearing portion 52^b. The outer end is or may be offset to prevent displacement of the three parts. The dished plate co-operates with the outer face of the ratchet wheel 73 to provide a groove or V-opening indicated at 75 in which is received a coiled brake spring 76 which passes over the top of the plate 74 and down at the front and rear sides thereof, the ends of said spring being secured to screws 77 screwed into the inner face of the right-hand side plate 42, Figs. 5 and 7. The brake spring co-operates with the supply carrier to prevent spin and consequent excess winding off of the tally work sheet, the spring applying a requisite amount of friction to the otherwise freely revoluble carrier or mandrel, and at the same time providing a reaction or take-up for the slight overthrow following each line spacing operation. This reaction is due to the tendency of the spring to return to normal position after the slight stretching of its coils as the tally strip is line spaced and the carrier 49 is turned. The ratchet wheel 73 constitutes one element of a detent device which is automatically operated by

the feed roll release as hereinafter explained to hold the carrier 49 from accidental turning movements at certain times.

The tally strip indicated in Fig. 7 of the drawing by the numeral 78 is usually applied in a roll which is wound on a supply core 79 of fiber, pasteboard or the like, this core being slipped over the core 50 of the supply carrier, the latter being withdrawn from the machine and the left-hand flange 53 being removed to facilitate the introduction of the wound-up tally strip 78. In order to prevent the tally core 79 from slipping on the core 50 of the carrier or spool, there is provided a pin 80 (Fig. 80 5) which passes transversely through the plug 52 and core 50 near the right-hand end of the latter and terminates in an outwardly projecting sharpened or knife-like end 81, said pin being adjustably secured in place by a set screw 82. When the tally roll is applied endwise to the core piece 50 the tally core 79, as it nears the right-hand end of the carrier or holder 49, will engage at its right-hand end with the knife portion 81 of the pin 80, which will split or cut the core 79 slightly without interfering with its being fully applied to the core piece 50 and will thus fix the tally roll on the carriage 49 and prevent any relative turning or slipping when the supply carrier is in place and in use.

As will be understood from Fig. 7, the free end of the tally strip 78 is led off from the back of the tally roll and behind the supply carrier 49 downward into the bight of the platen 12 and main feed roller 15, and thence under and around the platen and between it and the front feed roller 16 and up at the front side of the platen through and over devices hereinafter described and to the take-up or receiving device or rotary carrier for the tally. The take-up carrier designated as a whole by the numeral 83, best shown in Figs. 1, 5, 7 and 10, comprises a tubular body portion or sleeve 84, in the ends of which are fitted cylindrical plugs or closures 85 and 86. These end plugs are suitably secured in place so as to constitute with the sleeve 84 a single rotary member. The left-hand end plug 85 is provided at its outer surface with a series of ratchet teeth 87 to co-operate with a locking pawl or check to be later described. The ratchet teeth 87 are so cut however as not to interfere with the smooth contact of the plug 85 with the friction roller 45 as hereinafter set forth. The end plugs 85 and 86 are perforated to receive a rod or shaft 88 which extends longitudinally through the carrier 83 and constitutes an axle therefor. The end portions of the shaft 88 project outward through vertical slotways indicated at 89 formed in the frame plates 42, and these projecting portions are

formed with grooves 90 which receive garter springs 91 or coiled springs having their ends connected together. The springs 91 pass downward around the tie rod 36 at each side of the sub-frame and constantly urge axle 88 downward in its slotways or bearing openings 89, the result being that a constant downward pressure is applied to the tally receiving holder or carrier 83. The friction rollers 45 co-operate with the projecting end portions of the two heads or end plugs 85 and 86, these projecting portions being slightly less in diameter than the outer diameter of the tube 84, co-operating with said tube to provide circular depressions or ways indicated at 92 in which the friction rollers 45 are adapted to run. Said friction rollers loosely fit in said runways, so that while rotation on the sleeve 43 is not interfered with they are prevented from being displaced endwise along said sleeve. It will be understood that the spring pressure exerted by the springs 91 is transmitted through the carrier 83 to the friction rollers 45, said springs serving to maintain said rollers resiliently and co-operatively engaged with both the platen 12 and the carrier 83 with the result that line spacing or turning movements imparted to the platen will be transmitted through the rollers or idlers 45 to the carrier 83, causing the carrier to be turned automatically when the platen is line spaced or otherwise rotated. The slots 89 afford sufficient play to the carrier axle to allow for any unevenness or inequality that may arise in the course of the work. The free end of the tally strip 78 is led up at the front side of the carrier 83 and is suitably secured to the tube or core piece 84 as by a spring plate or clip 93 which may be of sheet metal curved to conform to the outer surface of the core 84 and arranged at the middle thereof, being secured along one of its edges to said core so that the advanced portion of the tally strip may be pushed under the free or spring edge of the clip and frictionally held thereby against detachment from the carrier 83. The construction is such that when the platen is line spaced or turned in the direction of the arrow in Fig. 7 the rollers or idlers 45 will be frictionally turned oppositely and the carrier 83 will be consequently turned counter-clockwise as indicated by its arrow to automatically take up the used portion of the tally strip.

The reproducing material or carbon strip designated by the numeral 94 (Fig. 7) is preferably in roll form and supported or carried by a rotary carrier or holder best shown in Figs. 1, 5 and 7. The carbon carrier or supporting device for the material or carbon paper 94 is designated as a whole by the numeral 95 and is arranged at the top of the sub-frame above the tally supply carrier 49. The carrier 95 comprises a metal tube or hollow core 96 which is provided with end plugs 97 and 98 fitted into its ends and secured in place as by set screws 99. Outside the tube the end plugs are so shaped that they provide grooves or seats from the annular heads or flanges 100. The plugs 97 and 98 are provided respectively with hub portion 97^a and 98^a which are perforated to afford passageway for a shaft or rod 101 on which the carbon carrier 95 is mounted. The shaft 101 extends centrally through the core 96 and its right-hand end portion bears in an opening in the right-hand frame plate 42, the shaft 101 being reduced as indicated at 101^a outside of said frame plate and threaded to receive a thumb nut or finger button 102. The left-hand projecting end portion of the shaft 101 carries a gear wheel or rotary member 103 having a function hereinafter described. Said gear wheel is provided with a hub 104 which bears in an opening in the left-hand frame plate 42, said hub outside said frame plate receiving a cross pin 105 whereby both the hub and the gear wheel 103 are fixedly secured to the shaft 101. It will be observed from Fig. 5 that the gear wheel 103 is arranged inside the frame plate 42, and also that the hub 98 and the inner end of the thumb nut 102 loosely confine the right-hand frame plate between them so as to prevent endwise displacement of the carrier 95 in either direction while affording free rotary movements thereof. The carrier 95 is provided with a spring clip 106 similar to the spring clip 93. Along one of its edges the spring clip 106 is secured to the core 96 as by rivets 107 leaving the other edge portion of the clip 106 free to allow the ends of the carbon paper 94 to be passed under it and frictionally and detachably secured to the carrier 95. As shown in Fig. 7 the carbon paper 94 is led off from the back of the roll of carbon and down behind the carrier 95, passing into the bight of the platen 12 and the feed roller 15 in register with but behind the tally strip 78 and thence around the platen and between it and the forward feed roller or pressure device 16 and upward past the printing point outside the tally strip 78.

The advanced portion of the carbon sheet or strip 94 above the printing line is preferably left free or unattached and in order properly to guide and manipulate the free end portion of the carbon, as well as the portion of the tally strip 78 between the platen and the holder 83, suitable devices are provided which are best illustrated in Figs. 1, and 5-9. Said devices comprise an inclined shelf or erasing plate 108 arranged above the platen, said shelf having lateral ears or extensions 109 terminating in beveled engaging portions 110 received in

beveled openings indicated at 111 formed in the lower end portions 42^a of the frame plates 42. These lower portions 42^a project forward and terminate in straight edges in which the beveled openings 111 are cut. 5 The construction provides for securely attaching the erasing plate 108 to the tally subframe, the beveled portion 110 of said plate fitting snugly in the openings 111, but 10 the plate is readily removable when the subframe is taken apart. The mounting of the erasing plate gives it a suitable inclination upward and rearward from the platen above the printing face thereof and the 15 lower edge portion of the plate 108 may be beveled at its rear side as at 108^a so as to fit closely to the platen and provide a practically continuous surface upward from the printing line and over the front face 20 of the plate 108. Spaced forward from the upper side of the erasing plate so as to provide a guide opening indicated at 112 between them is a knife blade or severing bar 113 which is supported near its ends 25 by headed pins 114 and 115. These pins are riveted or otherwise secured to the lateral portions 109 of the plate 108. Mounted on each pin back of the blade 113 is a spacing disk or washer 116 which separates the 30 blade 113 from the plate 108 sufficiently to provide the space or guide opening 112. The left-hand pin 114 serves as a pivot for the blade 113 and on which said blade may be swung upward as illustrated in Fig. 9. 35 The right-hand end portion of the blade 113 is provided with an open-end slot indicated at 117 which fits over a shoulder 115^a formed on the right-hand pin 115 behind its head, the construction securely locking 40 the blade in place, while the shoulder further assists to hold the washer 116 in proper position on the pin and prevents looseness or rattle. The upper edge portion of the blade is beveled or sharpened as indicated 45 at 113^b to provide a cutting edge against which both the carbon paper and the tally strip may be torn off by pulling forward, over and downward against said edge. Also the lower edge 113^b of the blade 113 may 50 be beveled to widen the entrance into the slotway or guide opening 112. A friction washer 114^a may be inserted under the head of the pivot pin 114 in a countersink in the left-hand portion of the blade 113. As appears from Fig. 7 both the tally strip 78 and the carbon strip 94 pass upward through 55 this opening 112 and the free end of the carbon is prevented from dropping forward by the blade 113. When, however, it is 60 desired to expose the printed portion of the tally strip above the printing line the blade 113 may be swung upward on its pivot 114, thus freeing the end portion of the carbon strip so that it may be pulled 65 forward exposing the writing on the under-

lying tally strip. If it be desired to correct or otherwise change the writing on the tally strip the erasing plate 108 affords a convenient surface against which erasures may be made. It will be observed that there 70 is thus provided a construction which permits ready access to the written portion of the tally strip or proof sheet at all times without removing it from the machine for purposes of inspection or the making of corrections. The mortise and tenon connections between the sub-frame and the erasing plate while affording as stated ready disconnection increases the rigidity and stability of the sub-frame. 75

80 From what has been said it will be understood that when the platen is turned in line spacing direction, both the tally strip and the carbon strip will be fed or line spaced by the co-operation between the platen and its paper feeding mechanism or feed roller devices 15 and 16, the tally and carbon delivery carriers or mandrels 49 and 95 being rotated as the material is unwound from them and fed over the platen, while the take-up carrier or holder 83 is also revolved through its connections 45 with the platen to wind on the used or written portion of the tally strip. In order to rewind or back feed the carbon so that it may be repeatedly 90 used for the reproduction of matter on the tally strip, there is provided rewind mechanism comprising a coiled spring 118 (Figs. 5 and 7) which surrounds the shaft 101 within the core 96, said spring being secured 100 at its right-hand end to the shaft, the left-hand end of said spring being hooked over the inner end of a pin 119 which is driven through the head 97 and projects from said head both inside and outside the carrier 95. 105 The outwardly projecting end portion of said pin operates as a stop device in co-operation with other stop devices to limit the turning movement of the carbon carrier 95 in opposite directions. The spring 118 opposes the turning of the carbon carrier to unwind the carbon therefrom and when the carbon is released from control of its feeding devices said spring operates to turn the carbon roll holder so as to rewind the carbon 115 paper thereon. The stop devices referred to comprise a rotary stop member or Geneva wheel 120 which is mounted on the gear wheel 103 at the inner face thereof, being pivoted on a shoulder pin 121 which is secured as by riveting to the wheel 103 near its periphery and projects laterally inwardly therefrom. The stop wheel 120 has two motions; a motion of rotation on its own axis 121 independently of the wheel 103, and a motion of revolution about the axis 101 which takes place when the wheel 120 is moved bodily during rotary movements of the gear wheel 103 on its axis 101. 120 The stop wheel or planetary stop 120 is 130

formed in the present instance with four radial slots 122, 123, 124 and 125 which are joined by curved faces 126, and there is also provided a closed or stop face 127 which is not slotted.

Before describing the co-operation between the pin stop 119 and the stop wheel 120 to limit turning movements of the carbon carrier in both directions I shall first 10 describe a novel feature of the present invention involving an automatic setting of the stop wheel or device 120 through progressively varying its bodily position, this being accomplished through a train of connections between the stop wheel and the paper feed releasing mechanism. Said train, which is illustrated in Figs. 1, 5 and 6, includes and begins with the gear wheel 103. Meshing with the gear wheel 103 at 15 its lower side is a small pinion 128, said pinion being mounted on the inner end of a stub shaft 129 which bears in an opening in the left-hand frame plate 42 and projects outwardly therethrough, the pinion 128 being arranged inside said frame plate. Outside said frame plate the stub shaft 129 carries a ratchet or toothed wheel 130 provided with a hub 131 which is secured by a pin 132 to said shaft 129. A pawl carrying arm or member 133 co-operates with said toothed wheel 130, the pawl member 133 being provided at its upper end with a laterally extending tooth 134 which is adapted to engage with a tooth of the wheel 130 at 20 its lower side. The lower end of the arm 133 terminates in a tail piece 135 and said arm is pivotally supported at 136 on a crank arm 137 which is provided with a squared hub 138 that fits over the rock shaft 39 outside the left-hand frame plate 42. The hub 138 has rounded corners 139 and receives two set screws 140 in two of them, being thus secured to the rock shaft 39 in such a way that the crank arm 137 projects rearward and slightly downward from said rock shaft so as properly to locate the pivot 136 of the pawl arm or member 133. The construction of the hub portion 138 and its mounting relative to the associate frame 25 plate 42 is brought out clearly in Fig. 5a. The hub member 138 is provided to the right of its main or body portion with a series of circular portions having graduated diameters numbered for the sake of clearness 30 138^a, 138^b, 138^c and 138^d, these portions forming shoulders with each other. The crank arm 137 is fitted over and staked or otherwise secured to the portion 138^b of the hub and abuts against the side face of the 35 portion 138^a, said crank arm being contiguous to the outer face of the frame plate 42. The hub portion 138^c bears in the bearing opening in said frame plate, and the portion 138^b which projects inwardly beyond 40 said frame plate has staked or otherwise se-

cured to it a collar 141. It will be observed that the frame plate is loosely embraced between the crank arm 137 and the collar 141, these parts with the portion 138^c forming in effect a groove in the collar, which while 45 affording free movements of rotation to the collar as a whole and the rock shaft 39, prevents endwise relative movement between the hub 138 and the frame plate. It may be said in passing that the screws 140 by which 50 the collar 141 is detachably secured to the rock shaft 39 also operate to secure or set the sub-frame 42, 43 and the parts mounted thereon in desired positions lengthwise of the carriage and platen and that it is only 55 necessary to loosen these screws to enable the sub-frame to be moved rightward on its supports longitudinally of the platen. The leftward movement requires the loosening of an additional screw of a pawl member 60 hereinafter described. Returning now to the connecting train or those elements of it leading down from the rock shaft 39 to the release shaft 17, said elements comprise 65 a crank arm 142, which is arranged on the 70 end portion of the rock shaft 39 projecting beyond the left-hand bracket 35, said crank arm being provided with a hub 143 which fits over said projecting portion of the rock shaft. The hub is square in cross section 75 with rounded corners 144, two of which receive set screws 145 whereby the hub and crank arm are fixed to the rock shaft, the crank arm projecting forward and slightly 80 downward therefrom. Pivots connected 85 by a headed pin or rivet 146 or other suitable device to the other end of the crank arm is a downwardly and rearwardly extending link 147 which terminates at its 90 lower end in a hook 148 which hooks over and under the offset portion 19 of the release key member 18-20. The link 147, 148 carries a latch 149 which is pivoted to it at 150. The lower end of the latch or arm 149 is curved at 151 on an arc struck from 95 the axis 150, this curved portion co-operating with the top portion of the offset 19 to maintain the hook engaged therewith. Near its upper end the arm 149 is depressed 100 to provide a bulge or projection 152 which 105 co-operates with a hole 153 in the link 147, to maintain the latch 149 in operative position. The latch has sufficient spring to enable the projection or detent device 152 to be withdrawn from the hole 153 so that the 110 latch may be swung on its pivot to one side, enabling the hook 148 to disconnect from the release key member 18, 20. It will be apparent that when the release shaft 17 is turned to release the feed rollers 15, 16, as 115 by actuating the key 20, the link 147, 148 will transmit this movement to the crank arm 142, rocking the shaft 39 and swinging the crank arm 137 upward, causing the pawl member 133, 134 to engage with the toothed 120

wheel 130 and turn it a predetermined extent comprising one or more units of distance in the direction of the arrow, Fig. 1, the predetermined extent of turning depending on the adjustment of the parts. Through the reducing connection provided by the small pinion 128 with the gear wheel 103, this movement of the ratchet wheel 130 will be reduced to about one-tenth when transmitted to the gear wheel 103 and will as a consequence move or advance the stop wheel or member 120 bodily a minute distance, preferably a small fraction of a line space distance. Co-operative with the wheel 130 is a detent pawl 154 pivoted at 155 to the outer face of the left-hand side frame 42 and connected by a draw-spring 156 with the pawl member 133. The tooth 154^a of the detent 154 acts as a stop to hold the wheel 130 in the positions to which it may be turned by the pawl member 133 and the spring 156 is effective on both the pawl member 133 and the detent member 154, maintaining the detent tooth 154^a engaged with the wheel 130 and keeping the pushing pawl tooth 134 against the rear edge of the frame plate 42 normally and as said tooth is moved up to engage with the wheel 130. The back of the frame plate thus serves as a guide for the pawl member 133, said member leaving its guide after engaging the wheel. The tail 135 of the pawl member 133 is adapted to co-operate with the hub 138 to prevent the pawl member 133 from being swung accidentally out of position. Without the tail 135 the pawl might be swung so far on its pivot that the spring 156 would pull on the opposite side thereof to hold the pawl member in inoperative position. The detent 154^a acting through the connections to the shaft 101 is effective to hold the inner end of the spring 118 during unwinding of the carbon paper.

From what has been said it will be understood that each time the shaft 17 is actuated and the feed release key member 18, 20 is swung backward either by hand as herein described (or automatically during the carriage travel, which is a method sometimes employed in the No. 11 Remington typewriting machine) the feed rollers 15 and 16 will be released and an impulse will also be transmitted through the described train of connections including the link 147, 148, crank arm 142, rock shaft 39, crank arm 137, pawl member 133, 134 and gear train 130, 128, 103, to the stop device or wheel 120. The normal position of the above parts is illustrated in Fig. 1, while the operated position is shown in Fig. 6. Assuming the stop wheel 120 to start from the position illustrated in Fig. 1, each of these impulses received when the feed rollers are released will advance or move said stop wheel bodily in the direction of the ar-

row in Fig. 1, resulting in the progressive step-by-step advance of the stop face 127. This result is illustrated in Fig. 4 which is drawn on an enlarged scale and showing the first position of the stop wheel 120 and stop pin 119 in full lines, with the stop face 127 engaged by said pin in correspondence with the position of the parts in Fig. 1. In Fig. 4 several progressive steps or advances of the stop wheel 120 and its stopping face 127 are illustrated by dotted line positions of the parts, and as clearly appears the result will be that the stop pin 119 will be arrested at successive points in advance of its first position. In other words, supposing the platen to be line spaced or turned to feed the tally strip and turn the carbon roll carrier 95, thus carrying the pin 119 away from the stop face 127 and winding up the spring 118, it will be understood that on releasing the feed rollers and freeing the carbon the stop face 127 will receive automatically an advance movement so that as the carbon is rewound and the carrier 95 turned back it will be arrested in advance of the position from which it started by reason of the contact of the stop pin 119 with the stop face 127 in its new position. The progressive change of position of the carbon carrier does not affect its spring, since in all positions the normal relationship of the two ends of said spring is the same. By providing however automatic stop setting means whereby the position of arrest of the carbon carrier is progressively advanced as described there is introduced a valuable feature, especially in connection with such common work as ledger posting or the like where single line entries are the rule. In such cases so short a section of carbon will be brought into play that it would very quickly become exhausted and would soon require, a readjustment of the stopping point on the rewind. Assuming however that work of this character was being done and that the outer sheet 157 illustrated in Fig. 7 is one of those on which only a single entry is to be made, it will be understood that such entry will be printed on the sheet at the front side of the platen by the type bars 31 through the inking ribbon 32, the entry being duplicated through the carbon 94 which is behind the work sheet 157 on the underlying tally strip 78, the carbon face of the paper 94 of course being turned inward so that it is in contact with the outer face of the tally strip 78. The writing on the latter having been completed the platen may be restored from left to right and line spaced by operating the handle 29, and the feed roller release may be actuated to free the sheet 157 so that it may be withdrawn and replaced by a new sheet. Such actuation of the release will result as described in an advance or step forward of the stop 120 and 125 130

a consequent slight alteration in the normal position of the carbon roll, thus correspondingly changing the line on the carbon at which the next imprints will be made. In other words, the carbon is very slowly advanced or so that the surface may be in effect completely used or worn before being discarded. It will be apparent also that the position of the carbon roll may be thus altered while the stop pin 119 is in engagement with the arresting face 127.

In cases where the work is left in the machine for the entry of many items it will be understood that as a result of frequent line spacing operations and the consequent extended advance of the carbon sheet and rotation of the carbon carrier 95, it might be that said carrier would be required to turn through several complete revolutions. In order to permit of a number of these turning movements and also to limit the number so as to prevent undue winding of the carbon restoring spring and other harmful results, the stop 120 has been made in the form of a Geneva stop as has been described. Assuming that the parts start from a normal position such as illustrated in Fig. 1 and that the platen is turned to advance the carbon and rotate the carbon carrier, it will be understood that as said carrier rotates it will carry with it the pin 119 which will eventually engage with the opening or slot 122, shown as located at the front side of the stop wheel when the parts are disposed as in Fig. 1. Further turning after such engagement will cause the pin 119 to advance in the slot 122 and press against the left-hand side thereof to turn the stop wheel 120 on its own axis 121, the cutout 119^a permitting such turning movement of the stop 120 without obstruction from the hub 97^a. The turning movement of the stop 120 on its own axis will continue as the pin 119 passes directly under said axis backward and downward, and until, as illustrated in Fig. 2, said pin starts to leave or disengage from the slot 122. Comparing Fig. 2 with Fig. 1 it will be observed that the stop wheel 120 has been turned on its axis in the direction of the arrow, Fig. 2, so as to bring the next succeeding slot 123 in the wheel into position to be engaged by the pin 119 after it has made another turn with the carbon roll and as it again approaches the end of its movement, whereupon the operation will be repeated on the wheel 120 turned another step through co-operation of the pin 119 and slot 123. It will be further understood from Figs. 1 and 2 that the curved faces 126 in the stop wheel successively permit rotation of the hub 97^a without obstruction from said stop wheel. It will further be understood that at each successive turning of the carbon carrier 95 the wheel 120 will

receive a turning movement due to successive engagements of the pin 119 with the slots 122, 123, 124 and 125 so that as the fifth turning movement of the carbon carrier begins, the stop wheel will occupy 70 the position illustrated in Fig. 3 with the closed face 127 in the path of the stop pin 119. Consequently as the carbon carrier approaches the end of its fifth rotation the stop 119 will be brought into contact with 75 the stop face 127 as illustrated in Fig. 3, preventing further rotation of the carbon carrier. However, the several rotations afforded the carbon carrier by the described construction is sufficient to allow for the 80 completion of the writing of the longest work sheet employed in practical work before the stops 119 and 127 will co-operate as in Fig. 3. It will be understood that after the writing has been completed and 85 the carbon paper is released, the backward rotation of the carrier under the impulse of its rewinding spring 118 will permit the stop pin 119 to co-operate with the slots in the wheel 120 in reverse order, causing a 90 backward or reverse rotation of said wheel on its axis until it is restored to normal position or with the stop face in position to arrest the stop pin 119 at the completion 95 of the rewinding movement. The stop 120 it will be observed is in effect a planetary stop, its motion of rotation on its own axis 121 through co-operation of the pin 119 with the slots in said planetary stop, as illustrated in Figs. 1, 2 and 3, being distinct 100 from the bodily revolution of said planetary stop about the axis 101 as illustrated in Fig. 4.

By throwing out the detent tooth 154^a temporarily the carbon carrier 95 will be 105 freed so that it may be readily rotated by the finger wheel 102 for the purpose of adjusting the carbon on the carrier 95 by hand movements.

There are also provided detent or safety 110 devices for the supply carrier 49 and the take-up carrier 83. As has been described the supply carrier mounts a ratchet wheel 73. Co-operative with this ratchet wheel is a pawl 158 (Figs. 5 and 7) which is provided 115 with a hub 159 fitted over the rock shaft 39 and secured thereto by a set screw 160. The pawl extends upward and rearward from the rock shaft and is separated from the ratchet wheel 73. However, when the rock 120 shaft 39 is actuated during the feed roll releasing operation the pawl 158 is swung automatically into engagement with the ratchet wheel 73 so as to prevent unwinding 125 of the tally strip 78 from the delivery roll. This device is especially useful when sheets are inserted from the rear or withdrawn from the front, as such sheets are liable to accidentally feed or advance the tally strip through frictional engagement therewith. 130

This is particularly true when a wide record sheet is retained in the machine by margin feed rollers as in some Remington billing machines. The automatically operated 5 detent devices 73, 158 hold the roll carrier and thus prevent such accidental feeding. Further there is provided a gravity pawl (Figs. 1 and 5) said pawl being in the form of a curved member 161 pivoted at 162 to 10 the inner face of the left-hand frame plate 42. Said pawl is provided with a tooth 163 which normally engages with the teeth of the ratchet wheel 87 so as to prevent backward rotation of the receiving carrier 83. 15 The tooth portion 163 of the pawl member 161 extends down back of the pivot as shown in Fig. 1. Forward of the pivot the pawl member 161 is provided with a downwardly extending horn or finger portion 164 which 20 may be pushed against and held when it is desired to free the carrier from its detent device or pawl tooth 163 so as to free said carrier for rotation in a direction to permit the paper to be withdrawn, usually when it 25 is to be severed and removed from the machine after having been written on.

When it is desired to readjust the tally carrying sub-frame 42, 43 along its supporting rod from right to left it is necessary to 30 loosen the screw 160 as well as the screws 140 as a preliminary. The two screws 140 must also be loosened prior to resetting or readjusting the contrivance on its support in a rightward direction, and it is desirable 35 if not strictly necessary that the screw 160 be also loosened at this time. It will be observed that the resetting of the tally contrivance proper on its supporting frame may 40 be readily and quickly effected since it involves only the loosening of three screws to enable this to be accomplished.

Various changes may be made without departing from the spirit and scope of my invention.

45 What I claim as new and desire to secure by Letters Patent, is:—

1. In a typewriting machine, the combination of a platen carriage, a platen, a tally contrivance proper, and a support therefor comprising a pair of brackets pivotally supported on the carriage and a tie rod connecting said brackets, said support maintaining said tally contrivance at rest against the platen.

55 2. In a typewriting machine, the combination of a platen carriage, a platen, a tally contrivance proper, a support therefor comprising a pair of brackets pivotally supported on the carriage, and a tie rod connecting said brackets, and spring means tending constantly to maintain said tally contrivance in co-operation with the platen.

60 3. In a typewriting machine, the combination of a platen carriage, a platen, a tally contrivance proper, a support therefor

comprising a pair of brackets pivotally supported on the carriage, and a tie rod connecting said brackets and supporting said tally contrivance, and a pair of coiled draw springs anchored to the carriage and each 70 connected to one of said brackets.

4. In a typewriting machine, the combination of a platen carriage, a platen, a tally contrivance proper, a support therefor comprising a pair of brackets pivotally supported on the carriage, and a tie rod connecting said brackets and supporting said tally contrivance, a pair of coiled draw springs anchored to the carriage and each 75 connected to one of said brackets, and friction rollers on said tally contrivance and which are maintained in frictional engagement with the platen by said draw springs.

5. In a typewriting machine, the combination of a platen carriage, a platen, a tally carrying contrivance proper, a pair of friction rollers, and a support for said contrivance comprising a pair of angular members spaced apart and rigidly connected by a tie rod, said support being pivoted to the carriage, said contrivance being adjustably mounted lengthwise of said tie rod, said friction rollers operatively engaging with the platen so as to receive rotary movements therefrom.

6. In a typewriting machine, the combination of a platen carriage, a platen shiftable to change case, feed rollers extending along the platen, a tally carrying contrivance proper, and a support for said contrivance comprising a pair of angular members spaced apart and rigidly connected by a tie rod, said support being pivoted to the carriage and shiftable with the platen, a second rod or bar mounted on said support, said contrivance being adjustably mounted lengthwise of said tie rod and said second rod or bar, said friction rollers operatively engaging with the platen so as to receive rotary movements therefrom in both shift positions of the platen.

7. In a typewriting machine, the combination of a platen, a traveling platen carriage comprising a truck and a platen frame, said platen frame and platen being shiftable on said truck to change case, feed rollers extending along the platen, a tally contrivance proper having parts engaging with said platen, and a support for said contrivance, said support being connected to said truck for affording shifting movements of said contrivance during case shifting movements of said platen and platen frame, said contrivance being adjustable lengthwise of said platen and its feed rollers.

8. In a typewriting machine, the combination of a platen, a traveling platen carriage comprising a truck and a platen frame, said platen frame and platen being shiftable on said truck to change case, feed rollers ex-

- 5 tending along the platen, a tally contrivance proper having parts engaging with said platen, a support for said contrivance along which it is adjustable, said support comprising a pair of brackets spaced apart and connected by a tie rod on which said contrivance is adjustable lengthwise of the platen, said brackets being pivotally connected to said truck, and spring means on said carriage and connected to said truck, said spring means constantly urging said contrivance towards the platen.

10 9. In a front strike typewriting machine, the combination of a platen carriage comprising a truck and a platen frame, a platen, said truck comprising front and rear bars between which said platen and said platen frame are arranged, the platen and platen frame being shiftable to change case, feed rollers extending along the platen, a tally contrivance proper that constantly rests on top of the platen, and a swinging support for said contrivance, said support comprising side brackets which are pivoted to the front part of said truck and extend rearward therefrom being connected by a tie rod extending lengthwise of and over the platen and whereon said contrivance is slidably supported.

15 10. In a front strike typewriting machine, the combination of a platen, a platen carriage comprising a truck and a platen frame, said truck comprising front and rear bars between which said platen and said platen frame are arranged, the platen and platen frame being shiftable to change case, feed rollers extending along the platen, a tally contrivance proper that constantly rests on top of the platen, a swinging support for said contrivance, said support comprising side brackets which are pivoted to the front part of said truck and extend rearward therefrom being connected by a tie rod extending lengthwise of and over the platen and whereon said contrivance is slidably supported, and coiled springs, one for each bracket, said coiled springs being anchored to the carriage and tending constantly to pull said support down toward the top of the platen and to maintain said contrivance in contact with said platen.

20 11. In a front strike typewriting machine, the combination of a platen; a platen carriage comprising a truck and a platen frame, said truck comprising front and rear bars between which said platen and said platen frame are arranged, the platen and platen frame being shiftable to change case; feed rollers extending along the platen; a tally carrying contrivance proper that rests resiliently on top of the platen and comprises upright side frames and a connecting hollow rod or sleeve; a swinging support for said contrivance, said support comprising side brackets which are pivoted to the front of

25 said truck and extend rearward therefrom, and a tie rod connecting said brackets and extending lengthwise of and over the platen, said sleeve being slidably supported on said tie rod; and spring means tending constantly to pull said support downward toward the top of the platen and to maintain said contrivance contactive with said platen.

30 12. In a front strike typewriting machine, the combination of a platen; a platen carriage comprising a truck and a platen frame, said truck comprising front and rear bars between which said platen and said platen frame are arranged, the platen and platen frame being shiftable to change case; feed rollers extending along the platen; a tally carrying contrivance proper that constantly rests on top of the platen and comprises upright side frames, a connecting hollow rod or sleeve and friction rollers loose on said sleeve; a support for said contrivance pivotally connected to said truck and comprising side members and a connecting tie rod passing through said sleeve; and spring means effective on said swinging support to maintain said friction rollers in contactive engagement with the top of the platen.

35 13. In a typewriting machine, the combination of platen carriage, a platen thereon, a tally carrying contrivance, and means for maintaining said contrivance in resilient engagement with said platen.

40 14. In a typewriting machine, the combination of a traveling platen carriage, a platen thereon, a support on said carriage, a tally contrivance proper mounted on said support and carrying a tally strip, and means acting through said support to maintain said contrivance in resilient contact with the platen.

45 15. In a typewriting machine, the combination of a traveling platen carriage, a platen thereon, a support on said carriage, a tally contrivance proper mounted on said support, means for affording adjustment of said contrivance on its support lengthwise of said platen, and spring devices acting through said support to maintain said contrivance in all its adjusted positions in resilient engagement with said platen.

50 16. In a typewriting machine, the combination of a traveling carriage comprising a truck and a platen frame, a platen on said frame, said platen and platen frame being shiftable on said truck to change case, a support on said truck, a tally contrivance proper on said support, and spring means acting through said support to maintain said contrivance in resilient engagement with said platen in both of its shift positions.

55 17. In a typewriting machine, the combination of a platen, a feed roller device extending lengthwise thereof, and a tally strip carrying contrivance adjustable lengthwise

of the platen to move the tally strip as a whole and in constant relationship to the carrying contrivance so that the tally strip may co-operate with the platen and said 5 feed roller device at any desired position lengthwise of the platen.

18. In a typewriting machine, the combination of a platen carriage, a cylindrical platen thereon, a set of feed rollers extending 10 lengthwise of said platen, and a tally carrying contrivance adjustably mounted on said carriage and settable at any desired position along the platen for co-operation with the platen and the feed rollers, the 15 tally strip being moved as a whole with the tally carrying contrivance and in constant relationship therewith and being fed from and to the contrivance and around the platen by reason of the co-operation between the 20 platen and the feed rollers when the platen is turned.

19. In a typewriting machine, the combination of a carriage, a platen thereon, a feed roller extending lengthwise of said 25 platen, a sub-frame on said carriage, a carrier for a tally strip mounted on said sub-frame, and means for affording adjustment of said sub-frame on said carriage so that said tally strip as a whole may be adjusted 30 with the sub-frame and in constant relationship herewith and may be brought into co-operation with the platen and its feed roller at any desired position lengthwise of the platen.

35 20. In a typewriting machine, the combination of a carriage, a platen thereon, a feed roller extending lengthwise of said platen, a sub-frame on said carriage, a carrier for a tally strip mounted on said sub-frame, friction rollers carried by said sub-frame, means for affording adjustment of 40 said sub-frame on said carriage so that said tally strip may be caused to co-operate with the platen and its feed roller at any desired 45 position lengthwise of the platen, and spring means for maintaining said friction rollers in resilient engagement with said platen in all of its adjusted positions.

50 21. In a typewriting machine, the combination of a platen, a platen carriage, a supporting device on the carriage and comprising a rod extending lengthwise of said platen, a sub-frame comprising plates and a sleeve rigid therewith and slidable on said 55 rod, and carriers for a tally strip and for carbon paper mounted on said sub-frame, said sub-frame being yieldingly supported on the platen and adjustable along said rod lengthwise of said platen.

60 22. In a typewriting machine, the combination of a platen, a platen carriage, a supporting device on the carriage and comprising a tie rod extending lengthwise of said platen, a sub-frame comprising vertically disposed plates and a sleeve rigid

therewith and slidable on said tie rod, carriers for delivering and taking up a tally strip, and frictional connections between said platen and the carrier on which the tally strip is taken up, said connections being mounted on said sleeve. 70

23. In a typewriting machine, the combination of a platen, a platen carriage, a supporting device on the carriage and comprising a rod, a sub-frame comprising plates and a sleeve rigid therewith and slidable on said rod, carriers for delivering and taking up a tally strip, a carbon carrier, said carriers being mounted on said sub-frame, and friction rollers on said sleeve coacting both 80 with said platen and with said take-up carrier.

24. In a typewriting machine, the combination of a platen, a platen carriage, a supporting device on the carriage and comprising a rod, a sub-frame comprising plates and a sleeve rigid therewith and slidable on said rod, carriers for delivering and receiving a tally strip, friction rollers on said sleeve co-acting both with said platen and 90 with said take-up carrier, spring means connected with said supporting device and assisting to maintain said rollers in operative contact with the platen, and separate spring means for maintaining said friction rollers 95 and said take-up carrier in operative contact.

25. In a typewriting machine, the combination of a platen, a platen carriage, a supporting device on the carriage and comprising a tie rod, a sub-frame comprising plates and a sleeve rigid therewith and slidable on said tie rod, a rotary take-up carrier for a tally strip mounted on said sub-frame, friction rollers rotatable on said sleeve, spring means on said supporting device to press said friction rollers towards the platen, and spring means on said take-up carrier to press said carrier towards said friction rollers. 100 105 110

26. In a typewriting machine, the combination of a platen, a platen carriage, a supporting device on the carriage and comprising a tie rod, a sub-frame comprising plates and a sleeve rigid therewith and slidable on said tie rod, a rotary take-up carrier for a tally strip, said carrier being provided with a shaft or axle extending through slots in said plates, draw-springs connected to said shaft outside said plates and also connected to said tie rod, and spring means constantly urging said supporting device towards said platen. 115 120

27. In a typewriting machine, the combination of a platen, a platen carriage, a supporting device on the carriage and comprising a tie rod, a sub-frame comprising plates and a sleeve rigid therewith and slidable on said tie rod, carriers for a tally strip and for carbon paper mounted on said sub- 125 130

frame, an automatic rewinding device for one of said carriers, stop devices associated with said last mentioned carrier to vary the extent of rewind, and means for automatically setting said stop devices, said automatic means including a rock shaft mounted on said supporting device and extending through and supporting said plates.

28. In a typewriting machine, the combination of a platen, a platen carriage, feed rollers, releasing devices therefor including a key, a supporting device on the carriage and comprising a rod, a sub-frame comprising plates and a sleeve rigid therewith and slidable on said rod, carriers for a tally strip and for carbon paper mounted on said sub-frame, an automatic rewinding device for one of said carriers, stop devices associated with said last mentioned carrier to vary the extent of rewind, a rock shaft mounted on said supporting device and extending through and supporting said plates, connections between said key and said rock shaft, and connections between said rock shaft and certain of said stop devices whereby the actuation of said key to release said feed rollers is automatically effective to vary said stop devices.

29. In a typewriting machine, the combination of a platen, a platen carriage, a supporting device on the carriage and comprising a tie rod extending lengthwise of said platen, a sub-frame comprising vertically disposed plates and a sleeve rigid therewith and slidable on said tie rod, carriers for a tally strip and for carbon paper mounted on said sub-frame, an automatic rewinding device for one of said carriers, stop devices associated with said last mentioned carrier to vary the extent of rewind, a rock shaft mounted on said supporting device and extending through and supporting said plates, a crank arm on said rock shaft, a link detachably connecting said crank arm with said key, a second crank arm on said rock shaft, a pawl on said second crank arm, and a gear train operative by said pawl and effective to reset certain of said stop devices.

30. In a typewriting machine, the combination of a platen, a platen carriage, a supporting device on the carriage and comprising a tie rod extending lengthwise of said platen, a sub-frame comprising vertically disposed plates and a sleeve rigid therewith and slidable on said tie rod, carriers for a tally strip and for carbon paper mounted on said sub-frame, an automatic rewinding device for one of said carriers, stop devices associated with said last mentioned carrier to vary the extent of rewind, a rock shaft mounted on said supporting device and extending through and supporting said plates, a crank arm on said rock shaft, a link detachably connecting said crank arm with said key, a second crank arm on said rock

shaft, a pawl on said second crank arm, a gear train operative by said pawl and effective to reset certain of said stop devices, and a detent effective through said gear train to retain the settable stop devices in set positions.

31. In a typewriting machine, the combination of a platen carriage, a platen, a sub-frame for a tally strip mounted on said carriage, a rotary carrier for taking up the tally strip mounted on said sub-frame, resilient connections independent of the tally strip between said platen and said carrier, and releasable devices for normally preventing the unwinding of the tally strip from said take-up carrier.

32. In a typewriting machine, the combination of a platen carriage, a platen, a sub-frame for a tally strip mounted on said carriage, rotary carriers for delivering and taking up the tally strip mounted on said sub-frame, and devices co-operative with the platen for unwinding the paper from one carrier and winding it on the other carrier when the platen is turned.

33. In a typewriting machine, the combination of a platen, paper feeding devices co-operative with said platen, a tally strip mechanism comprising rotary carriers for delivering a tally strip to the platen and taking it up after it has been written on and leaves the platen, devices for actuating both of said carriers automatically during platen turning movements.

34. In a typewriting machine, the combination of a platen, paper feeding devices co-operative with said platen, a tally strip mechanism comprising rotary carriers for delivering a tally strip to the platen and taking it up after it has been written on and leaves the platen, devices whereby both of said carriers are automatically actuated during platen turning movements, said devices comprising mechanical connections between the platen and the take-up carrier, and detent devices associated with said carriers and adapted to prevent turning movements thereof in one direction.

35. In a typewriting machine, the combination of a platen, paper feeding devices co-operative with said platen, a tally strip mechanism comprising rotary carriers for delivering a tally strip to the platen and taking it up after it has been written on and leaves the platen, and detent devices associated with said carriers and operative to prevent turning movements thereof in one direction, the detent devices for one of said carriers being normally effective and the detent devices for the other carrier being normally ineffective.

36. In a typewriting machine, the combination of a platen, paper feeding devices co-operative with said platen, a tally strip mechanism comprising rotary carriers for

delivering a tally strip to the platen and taking it up after it has been written on and leaves the platen, detent devices associated with said carriers and operative to prevent turning movements thereof in one direction, 5 the detent devices for one of said carriers being normally effective and the detent devices for the other carrier being normally ineffective, and means for rendering the ineffective detent devices operative, said means 10 acting automatically when said paper feeding devices are released.

37. In a typewriting machine, the combination of a platen carriage, a platen, a 15 tally delivery carrier provided with a ratchet wheel, a tally receiving carrier provided with a ratchet wheel, an arresting pawl normally co-operating with the ratchet wheel of said receiving carrier, and a pawl co-operative 20 with the ratchet wheel of said delivery carrier but normally ineffective.

38. In a typewriting machine, the combination of a platen carriage, a platen, tally 25 strip mechanism comprising a frame, a tally delivery carrier on said frame, said carrier being provided with a ratchet wheel, a tally receiving carrier on said frame and provided with a ratchet wheel, a pawl mounted 30 on said frame and normally co-operating with the ratchet wheel of said receiving carrier, and a pawl adapted to co-operate with the ratchet wheel of said delivery carrier but normally ineffective to arrest said delivery carrier.

39. In a typewriting machine, the combination of a platen carriage, a platen, 35 releasable paper feeding devices co-operative with said platen, tally strip mechanism comprising a frame, a tally delivery carrier on said frame, said carrier being provided with a ratchet wheel, a tally receiving carrier on said frame and provided with a ratchet wheel, a detent pawl mounted on said frame and normally co-operating with the ratchet 40 wheel of said receiving carrier, and a detent pawl for co-operating with the ratchet wheel of said delivery carrier but normally ineffective, said last recited pawl becoming 45 automatically effective when said paper feeding devices are released.

40. In tally strip mechanism for a typewriting machine, the combination of a rotary tally strip carrier, means for turning said carrier to feed the tally strip, and brake 55 devices for said carrier to prevent overthrow thereof, said brake devices comprising a grooved wheel connected with said carrier and a coiled brake spring engaging with said grooved wheel.

41. In tally strip mechanism for a typewriting machine, the combination of a rotary tally strip carrier, means for turning said carrier to feed the tally strip, and brake 60 devices for said carrier to prevent overthrow thereof, said brake devices comprising a 65

grooved wheel connected with said carrier and a coiled spring engaging with said grooved wheel, and partly surrounding the same, the ends of said coiled spring being secured against movement. 70

42. In tally strip mechanism for typewriting machines, the combination of a frame comprising plates spaced apart, and a rotary carrier mounted on said frame and provided with a spring mounted axle pin bearing in one of said end plates, said pin being movable endwise to disengage from said end plate so as to permit the carrier to be removed from the frame. 75

43. In a tally strip mechanism for typewriting machines, the combination of a frame comprising end plates, a rotary carrier mounted on said frame and provided with a spring mounted axle pin bearing in one of said end plates, said pin being movable endwise to disengage from said end plate so as to permit the carrier to be removed from the frame, and a spring pressed hand-controlled key co-operative with the opposite end portion of said carrier, said key being rotatable by hand to turn the carrier but being disconnectible at will from said carrier. 80 85 90

44. In a tally strip mechanism for typewriting machines, the combination of a frame comprising plates spaced apart, and a rotary carrier mounted on said frame and provided with a spring pressed hand controlled key mounted on said frame and normally co-operative with said carrier, said key being adapted to turn said carrier but being disconnectible at will from said carrier. 95 100

45. In a typewriting machine, the combination of a platen, a device for supporting material to be fed over the platen, feeding mechanism co-operative with the platen to feed said material, said device being movable to permit said material thus to be fed, and automatically varying stop means for 105 said device. 110

46. In a typewriting machine, the combination of a platen, a device for supporting material to be fed over the platen, feeding mechanism co-operative with the platen to feed said material, said device being movable to permit said material thus to be fed, a stop for said device, and automatic stop setting means. 115

47. In a typewriting machine, the combination of a platen, a device for supporting material to be fed over the platen, feeding mechanism co-operative with the platen to feed said material, said device being movable to permit said material thus to be fed, a stop for said device, and means for progressively varying the position of said stop. 120 125

48. In a typewriting machine, the combination of a platen, a device for supporting material to be fed over the platen, feeding 130

mechanism co-operative with the platen to feed said material, said device being movable to permit said material thus to be fed, releasing means for said feeding mechanism, 5 and a stop for said device connected to said releasing means.

49. In a typewriting machine, the combination of a platen, a device for supporting material to be fed over the platen, feeding 10 mechanism co-operative with the platen to feed said material, said device being movable to permit said material thus to be fed, releasing means for said feeding mechanism, a stop for said device, and connections 15 between said releasing means and said stop.

50. In a typewriting machine, the combination of a platen, a device for supporting material to be fed over the platen, feeding mechanism co-operative with the platen to 20 feed said material, said device being movable to permit said material thus to be fed, releasing means for said feeding mechanism, a stop for said device, and connections 25 between said releasing means and said stop whereby the position of said stop is altered step-by-step.

51. In a typewriting machine, the combination of a platen, feeding mechanism co-operative therewith, a device for supporting 30 material and movable to permit it to be fed, releasing means for said feeding mechanism, a stop for said device, and connections between 35 said releasing means and said stop whereby the position of said stop is altered step-by-step, said connections comprising a train of reducing gearing.

52. In a typewriting machine, the combination of a rotary platen, a rotary carrier 40 for supporting material to be fed over the platen, feeding mechanism co-operative with the platen to feed said material and turn said carrier, a stop on said carrier, a co-operating stop, and means for automatically varying the position of said co-operating 45 stop.

53. In a typewriting machine, the combination of a rotary platen, a rotary carrier 50 for supporting material to be fed over the platen, feeding mechanism co-operative with the platen to feed said material and turn said carrier, a stop on said carrier, a co-operating stop, and means operating automatically 55 to advance said co-operative stop step-by-step.

54. In a typewriting machine, the combination of a rotary platen, releasable paper feeding means co-operative therewith, a rotary carrier for carbon paper, a stop on said carrier, a co-operating stop, and means operating automatically 60 when the paper feeding means is released to advance said co-operating stop a predetermined distance.

55. In a typewriting machine, the combination of a platen, paper feeding mechanism, a carbon supporting device movable as 65

the carbon paper is fed over the platen, stop means determining the initial position of said carbon supporting device, and means for progressively varying said stop means.

56. In a typewriting machine, the combination of a platen, paper feeding mechanism, a carbon carrier from which carbon paper is led to the platen and fed thereover by said paper feeding means, said carrier being thereby moved, stop means determining the initial position from which said carrier is moved, and means for progressively varying said stop means. 70 75

57. In a typewriting machine, the combination of a platen, paper feeding mechanism, a carbon supporting device movable as the carbon paper is fed over the platen, stop means determining the initial position of said carbon supporting device, and means for automatically controlling said stop 80 85 means.

58. In a typewriting machine, the combination of a platen, paper feeding mechanism, a carbon controlling device movable as carbon paper is fed over the platen, stop 90 means determining the initial position of said carbon controlling device, and means operating automatically to progressively vary the position of said stop means.

59. In a typewriting machine, the combination of a platen, mechanism co-operative therewith to feed paper, a supporting device for material movable to afford a feeding of said material over the platen, stop 95 means determining the initial position of said device, and means for progressively varying said stop means, said last recited means being controlled from said mechanism. 100

60. In a typewriting machine, the combination of a platen, paper feeding mechanism, a device movable to afford feeding of carbon paper over the platen, stop means determining the initial position of said device, means for progressively varying said 105 stop means, means for releasing said paper feeding mechanism, and connections between said releasing means and said means for progressively varying the stop means. 110

61. In a typewriting machine, the combination of a platen, paper feeding mechanism, a carbon controlling device movable as the carbon paper is fed over the platen, restoring means operative to automatically restore said carbon controlling device to a starting position, stop devices for arresting said carbon controlling device in its starting position, and means for progressively varying the position of said stop devices so as to vary the starting position of said 115 carbon controlling device. 120

62. In a typewriting machine, the combination of a platen, feeding means co-operative therewith, a carrier for supporting material that is fed over the platen by said 125 130

feeding means, a stop connected with said carrier, a co-operating stop, and means operating to advance said co-operating stop a predetermined distance, said means including a train of reducing gearing whereby said predetermined distance is reduced to a fraction of a unit of line space distance.

63. In a typewriting machine, the combination of a platen, paper feeding mechanism co-operative therewith, devices for releasing said mechanism including a release shaft, a carrier for supporting material that is fed over the platen by said paper feeding mechanism, a stop on said carrier, a co-operating stop, and means operating automatically when the paper feeding mechanism is released to advance said co-operating stop a predetermined distance, said automatic means comprising a train of connections between said release key and said rotary carrier.

64. In a typewriting machine, the combination of a rotary platen, feeding mechanism co-operative therewith, devices for releasing said mechanism including a release shaft, a carrier for supporting material to be fed, a stop connected with said carrier, a co-operating stop, and means operating automatically when the feeding mechanism is released to advance said co-operating stop a predetermined distance, said automatic means comprising a pawl connected to said releasing shaft, and a train of gearing operated by said pawl and connected to said co-operating stop.

65. In a typewriting machine, the combination of a rotary platen, releasable paper feeding mechanism, a carrier for supporting material that is to be fed over the platen, a stop connected with said carrier, a co-operating stop, and means operating automatically when the paper feeding mechanism is released to advance said co-operating stop a predetermined distance, said automatic means comprising pawl and ratchet mechanism and reducing connections to said co-operative stop operative by said pawl and ratchet mechanism.

66. In a typewriting machine, the combination of a platen, paper feeding mechanism co-operative therewith, devices for releasing said mechanism including a release shaft, a carrier for supporting material that is fed over the platen by said paper feeding mechanism, a stop on said carrier, a co-operating stop, and means operating automatically to advance said co-operating stop a predetermined distance, said automatic means comprising a rock shaft provided with crank arms, a link connecting one of said crank arms with said release shaft, a pawl carried by one of said crank arms, and a toothed wheel operative by said pawl and connected to said co-operating stop.

67. In a typewriting machine, the combination of a platen, paper feeding mechanism co-operative therewith, devices for releasing said mechanism including a release shaft, a carrier for supporting material that is fed over the platen by said paper feeding mechanism, a stop on said carrier, a co-operating stop, and means operating automatically to advance said co-operating stop a predetermined distance, said automatic means comprising a toothed wheel, connections between said toothed wheel and said co-operative stop, a pawl connected to said release shaft and operative on said toothed wheel, and a detent for retaining said toothed wheel in the positions to which it is turned by said pawl.

68. In a typewriting machine, the combination of a platen, paper feeding mechanism co-operative therewith, devices for releasing said mechanism including a release shaft, a carrier for supporting material that is fed over the platen by said paper feeding mechanism, a stop on said carrier, a co-operating stop, and means operating automatically to advance said co-operating stop a predetermined distance, said automatic means comprising a toothed wheel, connections between said toothed wheel and said co-operative stop, a pawl connected to said release shaft and operative on said toothed wheel, and a detent for retaining said toothed wheel in the positions to which it is turned by said pawl.

69. In a typewriting machine, the combination of a platen, paper feeding mechanism co-operative therewith, devices for releasing said mechanism including a release shaft, a carrier for supporting material that is fed over the platen by said paper feeding mechanism, a stop on said carrier, a co-operating stop, and means operating automatically to advance said co-operating stop a predetermined distance, said automatic means comprising a toothed wheel, connections between said toothed wheel and said co-operative stop, a pivoted pawl arm provided with a tooth for actuating said toothed wheel, said pawl arm being connected to and operative by said release key, and a pivoted detent arm provided with a tooth engaging with said toothed wheel to hold it in set positions.

70. In a typewriting machine, the combination of a platen, releasable paper feeding mechanism, a carrier for supporting material that is to be fed, a stop connected to said carrier, a co-operating stop, and automatic means for advancing said co-operating stop a predetermined distance, said automatic means comprising a toothed wheel, a pawl

connected to said release shaft and operative on said wheel, a pinion coaxial with said wheel, and a gear wheel intermeshing with said pinion, said gear wheel supporting said co-operating stop.

71. In a typewriting machine, the combination of a platen, paper feeding mechanism co-operative therewith, devices for releasing said mechanism including a release shaft, a carrier for supporting material that is fed over the platen, a stop on said carrier, a co-operating Geneva stop, and automatic means to advance said co-operating stop a predetermined distance, said automatic means comprising a toothed wheel, a pawl connected to said release shaft and operative on said wheel, a pin coaxial with said wheel, and a gear wheel intermeshing with said pinion, said Geneva stop being pivotally supported on said gear wheel.

72. In a typewriting machine, the combination of a platen, paper feeding mechanism co-operative therewith, devices for releasing said mechanism including a release shaft, a carrier for supporting material that is fed over the platen, a stop on said carrier, a co-operating stop, and means operating automatically to advance said co-operating stop a predetermined distance, said automatic means comprising a gear wheel, and a train of reducing connections between said gear wheel and said release shaft, said co-operating stop being pivotally mounted on said gear wheel.

73. In a typewriting machine, the combination of a platen, paper feeding mechanism co-operative therewith, devices for releasing said mechanism including a release shaft, a carrier for supporting material that is fed over the platen, a stop connected to said carrier, a co-operating stop, and means operating automatically to advance said co-operating stop a predetermined distance, said automatic means comprising a rotary member, and connections between said rotary member and said paper feed releasing devices, said co-operating stop being mounted on said rotary member.

74. In a typewriting machine, the combination of a rotary platen, paper feeding mechanism co-operative therewith, devices for releasing said mechanism including a release shaft, a rotary carrier for supporting material that is fed over the platen, a stop connected to said carrier, a co-operating stop, and means operating automatically when the paper feeding mechanism is released to advance said co-operating stop a predetermined distance, said automatic means comprising a rotary member independent of said carrier but coaxial therewith, and connections between said rotary member and said paper feed releasing devices, said co-operating stop being connected to said rotary member.

75. In a typewriting machine, the combination of a rotary platen, paper feeding mechanism co-operative therewith, devices for releasing said mechanism including a release shaft, a rotary carrier for supporting material that is fed over the platen, a stop connected to said carrier, a co-operating stop, and means operating automatically when the paper feeding mechanism is released to advance said co-operating stop a predetermined distance, said automatic means comprising a rotary member independent of said carrier but coaxial therewith, and connections between said rotary member and said paper feed releasing devices, said co-operating stop being pivoted to said rotary member so as to be moved bodily when said member is rotated.

76. In a typewriting machine, the combination of a rotary platen, paper feeding mechanism co-operative therewith, devices for releasing said mechanism including a release shaft, a rotary carrier for supporting material that is fed over the platen, a stop connected to said carrier, a co-operating stop, and means operating automatically when the paper feeding mechanism is released to advance said co-operating stop a predetermined distance, said automatic means comprising a rotary member independent of said carrier but coaxial therewith, and connections between said rotary member and said paper feed releasing devices, said co-operating stop being connected to said rotary member, one of said stops being adapted to move the other to effective position.

77. In a typewriting machine, the combination of a rotary platen, paper feeding mechanism co-operative therewith, devices for releasing said mechanism including a release shaft, a rotary carrier for supporting material that is fed over the platen, a stop connected to said carrier, a co-operating stop, and means operating automatically when the paper feeding mechanism is released to advance said co-operating stop a predetermined distance, said automatic means comprising a rotary member independent of said carrier but coaxial therewith, and connections between said rotary member and said paper feed releasing devices, said co-operating stop being connected to said rotary member, one of said stops being adapted to move the other to effective position in opposite directions.

78. In a typewriting machine, the combination of a rotary platen, paper feeding mechanism co-operative therewith, devices for releasing said mechanism, a rotary carrier for supporting material that is fed over the platen, a stop on said carrier, a rotary stop co-operating with said carrier stop to arrest the carrier, and means operating automatically when the paper feeding mecha-

nism is released to advance said co-operating stop a predetermined distance, said automatic means comprising a rotary member and connections between said rotary member 5 and said paper feed releasing devices, said rotary stop being pivoted to said rotary member so as to be moved bodily when said member is rotated, the carrier stop being adapted to turn said rotary stop on its own 10 axis.

79. In a typewriting machine, the combination of a rotary platen, paper feeding mechanism co-operative therewith, devices for releasing said mechanism, a rotary carrier for supporting material that is fed over the platen, a stop connected to said carrier, a rotary stop co-operating with said first named stop to arrest the carrier, and means operating automatically when the paper 20 feeding mechanism is released to advance said co-operating stop a predetermined distance, said automatic means comprising a rotary member, and connections between said rotary member and said paper feed releasing devices, said rotary stop being pivoted to said rotary member so as to be moved bodily when said member is rotated and being provided with a series of slots with which said first named stop is adapted to engage successively so as to turn said rotary stop step-by-step on its own axis until its 30 arresting position is reached.

80. In a typewriting machine, the combination of a rotary platen, paper feeding mechanism, a rotary material carrier from which material is drawn by the platen and paper feeding mechanism, spring means for turning said carrier to rewind the material when released from control of the platen, 40 and two co-operating stops that are adapted to limit turning movements of said carrier in opposite directions.

81. In a typewriting machine, the combination of a rotary platen, paper feeding mechanism, a rotary material carrier from which material is drawn by the platen and paper feeding mechanism, spring means for turning said carrier to rewind the material when released from control of the platen, 45 and stop mechanism for said carrier comprising a stop connected to said carrier, a co-operating Geneva stop, and a rotary member on which said Geneva stop is pivoted.

82. In a typewriting machine, the combination of a platen, paper feeding mechanism, releasing devices for said mechanism, a rotary material carrier from which material is drawn over the platen, spring means for moving said carrier to return the material when released, and stop mechanism for said carrier comprising two co-operating stops that are adapted to limit movements of said carrier in opposite directions, said stop mechanism comprising a stop connected 60 to said carrier, a co-operating Geneva stop,

a rotary member on which said Geneva stop is pivoted, and operating connections between said rotary member and said releasing devices.

83. In a typewriting machine, the combination of a rotary platen, paper feeding mechanism, releasing devices for said mechanism, a rotary material carried from which material is drawn by the platen and paper feeding mechanism, spring means for turning said carrier to rewind the material when released from control of the platen, and stop mechanism for said carrier comprising two co-operating stops that are adapted to limit turning movements of said 70 carrier in opposite directions, said stop mechanism comprising a stop carried by said carrier, a co-operating Geneva stop, a rotary member on which said Geneva stop is pivoted, and operating connections between 75 said rotary member and said releasing devices, said Geneva stop being adapted to be turned step-by-step by said carrier stop during successive rotations of the carrier as the material is drawn off until said Geneva stop reaches its effective arresting position to prevent further turning of said carrier to advance the paper.

84. In a typewriting machine, the combination of a rotary platen, paper feeding mechanism, releasing devices for said mechanism, a rotary material carrier from which material is drawn over the platen, spring means for moving said carrier to return the material when released from control of the platen, and stop mechanism for said carrier comprising two co-operating stops that are adapted to limit movements of said carrier in opposite directions, said stop mechanism comprising a stop connected with said carrier, a co-operating Geneva stop, a rotary member on which said Geneva stop is pivoted, and operating connections between 90 said rotary member and said releasing devices, said Geneva stop being adapted to be turned a predetermined step by the other stop for each forward rotation of the carrier as the material is drawn off until said Geneva stop reaches its effective arresting position to prevent further turning of said carrier to advance the paper, and said Geneva stop being adapted to be correspondingly turned backward step by step until it reaches effective position to arrest the carrier during its reverse rotation.

85. In a front strike typewriting machine, the combination of a platen carriage, a platen thereon, tally strip mechanism comprising a supporting frame on said platen carriage, an erasing plate secured to said frame in position to receive the tally strip after it has been written on and has passed above the printing point, a receiving carrier for the tally strip arranged above said erasing plate, and a device on said frame 125

and spaced forward from said erasing plate providing a guide opening through which the tally strip and the overlying carbon strip may freely pass, said device preventing the free portion of the carbon strip from dropping forward but being movable independently of the erasing plate to a position to enable the carbon strip to be drawn forward freely to expose the underlying tally strip.

86. In a front strike typewriting machine, the combination of a platen carriage, a platen thereon, tally strip mechanism comprising a supporting frame on said platen carriage, an erasing plate secured to said frame in position to receive the tally strip after it has been written on and has passed above the printing point, a receiving carrier for the tally strip arranged above said erasing plate, and a severing blade on said frame and spaced forward from said erasing plate, said blade and said plate providing a guide opening for the tally strip and being relatively separable to enable a sheet to be drawn forward freely away from the front face of the platen.

87. In a typewriting machine, the combination of a platen carriage, a platen, a sub-frame on said platen carriage, a tally carrier on said sub-frame, an erasing plate on said sub-frame, and a severing blade associated with said erasing plate, the tally and carbon strips being adapted to pass between said erasing plate and said severing blade, said severing blade being pivoted at one end so that it may be swung to a position to enable the carbon strip to be pulled away from the underlying tally strip.

88. In a typewriting machine, the combination of a platen carriage, a platen, a

sub-frame on said platen carriage, a tally carrier on said sub-frame, an erasing plate on said sub-frame, and a severing blade associated with said erasing plate, the tally strip and its carbon being adapted to pass between said erasing plate and said severing blade, said severing blade being pivoted at one end and provided with a slot at the opposite end, the slot co-operating with a relatively fixed part to latch said blade in operative position, and the pivot of said blade enabling it to be swung out of the way so that the carbon strip may be pulled apart from the tally strip to expose the latter.

89. In a typewriting machine, the combination of a platen carriage, a platen, a sub-frame on said platen carriage, a tally carrier on said sub-frame, an erasing plate on said sub-frame, a pivoted severing blade, and spacing washers interposed between said severing blade and said erasing plate.

90. In a typewriting machine, the combination of a platen carriage, a platen, a sub-frame on said platen carriage, a tally carrier on said sub-frame, an erasing plate on said sub-frame, said erasing plate having mortise and tenon connections with said frame, a pivotally mounted severing blade normally parallel with said erasing plate, and spacing washers interposed between said severing blade and said erasing plate.

Signed at the borough of Manhattan, city of New York, in the county of New York and State of New York, this 21st day of June, A. D. 1922.
